(57) **CLAIM**

The ornamental design for a flash drive, as shown and described.

DESCRIPTION

FIG. 1 is a top, rear, right perspective view of a flash drive showing my new design;

FIG. 2 is a left side elevation view of the flash drive shown in FIG. 1, with the right side elevation view being a mirror image thereof;

FIG. 3 is a top plan view thereof;

FIG. 4 is a bottom plan view thereof;

FIG. 5 is a front elevation view thereof; and,

FIG. 6 is a rear elevation view thereof.
